UNITED STATES PATENT OFFICE.

SOLOMON C. SALZENSTEIN, OF PEORIA, ILLINOIS.

DESIGN FOR AN APRON.

42,566.

Specification for Design.

Patented May 28, 1912.

Application filed January 22, 1912. Serial No. 672,790. Term of patent 14 years.

To all whom it may concern:

Be it known that I, SOLOMON C. SALZENSTEIN, residing at Peoria, in the county of Peoria and State of Illinois, have invented a new, original, and ornamental Design for Aprons, of which the following is a specification, reference being had to the accompanying drawing, forming part thereof.

Figure 1 is a plan view of an apron showing my design; Fig. 2 is a perspective view of the same looking at an angle intermediate

the side and front thereof; Fig. 3 is a perspective view showing the apron in use.

I claim:

The design for an apron as herein shown. In testimony whereof, I have hereunto set my hand and affixed my seal at Peoria, Illinois, this 16th day of January, 1912.
